UNITED STATES PATENT OFFICE.

JOHN FRASER, OF HACKENSACK, NEW JERSEY.

PRESS FOR MAKING PIPES.

1,037,889.

Specification of Letters Patent. Patented Sept. 10, 1912.

Application filed November 20, 1909. Serial No. 529,114.

To all whom it may concern:

Be it known that I, JOHN FRASER, a citizen of the United States of America, residing in Hackensack, in the county of Bergen, 5 in the State of New Jersey, have invented a certain new and useful Improved Press for Making Pipes, of which the following is a specification.

My invention relates to the construction 10 of a press for squeezing lock bars on the upset edges of metal plates bent up into pipe form, to close the longitudinal joints to form sheet metal pipes.

My invention is more particularly intended 15 as an improvement upon the construction of such a press forming the subject of Patent No. 914,369, granted March 2, 1909, to myself and Thomas Gray.

The main object of my invention is to 20 so construct such a press as to increase the output especially for pipe sections of the smaller diameters, and each of which is made from a single sheet with but one longitudinal joint.

25 In the accompanying drawing Figure 1 is a plan view of my improved press; Fig. 2 is a sectional elevation.

As in the case of the press of the above mentioned patent, a pit A is constructed 30 deep enough for the longest pipe section to be formed, and at the mouth of the pit is mounted the horizontal press frame B, consisting of cross-heads b and b^1 united by the bars b^2 , the whole frame being suitably bolted 35 to the foundations. In a suitable foot piece F at the bottom of the pit, I mount three properly spaced vertical rods C, D and E, which severally carry at their tops in the plane of the press frame mandrels or 40 squeezing tools, C¹, D¹ and E¹ respectively, in line with each other.

The tube guiding and truing frame R is made to guide two tubes P, P¹, through at 45 a time, as shown in Fig. 1, with one squeezing tool C¹ within one tube, another tool E¹ within the other tube, and the intermediate tool D¹ between the two tubes. This frame R, which is provided with suitable antifriction rollers r to bear on the outer circumferences of the pipe sections at the desired 50 points, is so mounted upon the press frame B that it is free to move horizontally parallel with the line of the tools C¹, D¹, E¹, to accommodate itself and the pipes to the 55 movements of the tools, to the limited ex-

tent required. The most convenient way of arranging this is to mount the frame R upon the longitudinal bars b^2 , Fig. 1, so that it can move thereon and also so that it can be lifted off and replaced by another 60 frame for pipes of other diameters within the range of the machine.

Secured to the cross-head b is the stationary squeezing tool T in immediate coöperation with the tool C¹ in closing the lock-bar on the pipe P, while at T¹ is the reciprocating squeezing tool in immediate coöperation with the tool E¹ to close the lock-bar on the pipe P¹. The inward movement of the tool T¹ is sufficient not only to close 70 the lock-bar on pipe P¹, but also to force the diametrically opposite side of the pipe against the tool D¹, the latter against the pipe P, the latter against the tool C¹, and the latter to close the lock-bar of pipe P 75 with the aid of the coöperating fixed tool T.

Any suitable means may be provided to reciprocate the tool T¹. In the drawing I have shown for the sake of illustration the same mechanical means as are described in 80 the above mentioned patent and composing a crank shaft S driven from a motor M through suitable gearing 10, 11, 12 and 13, and hydraulic clutch 14.

I claim as my invention—

1. In an apparatus for closing longitudinal lock-bar pipe joints, a horizontal frame and guides for two pipes, said guides movable horizontally on the frame in combination with a series of squeezing tools in line 90 with each other, comprising a fixed tool on the frame, another tool reciprocating in the frame, and intermediate tools, upright rods for supporting said intermediate tools and means for actuating the reciprocating tool. 95

2. In an apparatus for closing longitudinal lock-bar pipe joints, the combination of guides for two pipes with a series of squeezing tools in line with each other, comprising a fixed and reciprocating tool and 100 intermediate tools, one within each pipe and one between adjacent pipes, substantially as described.

In testimony whereof I have signed my name to this specification, in the presence of 105 two subscribing witnesses.

JOHN FRASER.
